DISPENSER FOR COFFEE OR THE LIKE

Douglas A. Long, 14-D, 340 E. 80th St., New York, N.Y.

Filed Dec. 18, 1964, Ser. No. 33,078

Term of patent 14 years

(Cl. D2—3)

The figure is a perspective view of the front, and one side of a dispenser for coffee or the like showing my new design.

The dominant features of my design reside in the portion shown in full lines. The back, top and bottom of the machine are flat and unadorned.

I claim:

The ornamental design for dispenser for coffee or the like, as shown and described.
